RICHARD E. JEFFERY, OF PIEDMONT, CALIFORNIA.

FIREARM.

962,223.

Specification of Letters Patent. Patented June 21, 1910.

Application filed April 24, 1909. Serial No. 491,897.

To all whom it may concern:

Be it known that I, RICHARD E. JEFFERY, citizen of the United States, residing at Piedmont, in the county of Alameda and 5 State of California, have invented new and useful Improvements in Firearms, of which the following is a specification.

My invention relates to firearms.

The invention consists of the parts and 10 the construction and combination of parts as hereinafter more fully described and claimed, having reference to the accompanying drawings, in which—

Figure 1 is a section of the gun showing 15 the action in closed position. Fig. 2 is a similar view, the action being in firing position. Fig. 3 shows the action in loading position. Fig. 4 is a vertical transverse section on line X—X, Fig. 1. Fig. 5 is a 20 vertical transverse section on the line Y—Y of Fig. 1. Fig. 6 is a horizontal section, showing the action in plan. Fig. 7 is a detail of the breech closing mechanism. Fig. 8 is a perspective of the elevator. Fig. 9 is a 25 cross-section of same. Fig. 10 is a perspective of the case and breech-block.

A is the stock, and 2 is the receiver to which the stock is removably secured by means of a lengthwise extending mainspring 30 tube 3 carried by the stock and screwing into the receiver.

4 is a shaft extending through the tube 3 and actuated by the mainspring 5 by which the hammer 6 is operated; the spring 5 being 35 fixed at one end to the shaft, as shown at 7, and at the other end being fixed to a ratchet 8 loosely mounted in the butt of the stock for rotation independent of the shaft 4. The front end of the shaft is journaled in the 40 head of the tube and the butt end is supported on the pintle 9 belonging to the ratchet 8. The latter is wound up by inserting a suitable key or wrench into a hole in the butt and engaging the stem 10 of the 45 ratchet, the latter being held against rotation in one direction by the spring pawls 11.

The spring 5 is coiled around the shaft, and as the latter has a length substantially equal to the length of the stock, a considerable tension can be placed on the shaft, so as to cause it to act on the hammer to fire a great number of shots, as will be hereinafter more fully described. Manifestly by employing two sets of springs 5, one inside the

other, still greater tension can be put on the shaft.

The forward end of the shaft extends into the breech and carries a bevel pinion 12 acting on two opposed bevel gears 13—14; the gear 13 being fixed to the hammer 6, and 60 the gear 14 connectible and disconnectible with the gear 15 by which the breech-block 16 and breech locking brace 17 are operated. The several gears 13—14—15 are mounted on the pin-bolt 18; and the pinions 13—14 65 being always in mesh on opposite sides of pinion 12, consequently rotate in opposite directions.

The hammer 6 has a radial hammer projection to provide a striking face 6' which 70 is normally engaged by a sear lug 19 on the trigger 20, the trigger 20 being held up so that the sear lug 19 is normally in the path of the hammer by suitable means, as the spring 21. The trigger is pivoted at 22, 75 and ordinarily the trigger cannot be pulled when the safety catch 23 is in position behind the trigger, as shown in Fig. 1. In order to pull the trigger, the second finger is pressed up against the exposed end of the 80 safety catch 23 to release the trigger, as shown in Fig. 2. Releasing the trigger from the sear lug, and pulling it, causes the sear lug 19 to release the hammer, and the latter, acting through the gears 13—12 and 85 under the impulse of the mainspring 5, causes the hammer to swing around, and if the breech-block is in operative position the hammer will strike the firing-pin 24 and discharge the piece, provided the latter is 90 loaded. A certain safety provision is made by which, in case for any reason the sear lug 19 should break off, or the hammer should fly around accidentally, the piece cannot be discharged, and this safety provision 95 is accomplished through the means for supporting the breech-block and connecting it with the trigger; all as will be shortly described.

The breech-block 16 slides back and forth in suitable guides 25 in the breech 2, and has a rack tooth edge 26 always in engagement with the gear 15 which is loose on the pivot-pin 18 and is free to turn, and does turn, alternately in opposite directions on 100 the reciprocation of the breech-block. The breech locking brace 17 is pivoted in the front end of the breech block 16, as shown

at 27, and the breech block is made hollow on its under side so that the breech locking brace may be moved up into the breech block or be dropped down, to carry the firing-pin 6. 5 24 into or out of the path of the hammer 6. This raising and depressing, or oscillation, of the breech locking brace is accomplished by a rigid extension arm 28 on the trigger; this arm having its upper end provided with 10 a projection 30 engaging in a slot 31 in the breech locking brace to allow for the reciprocation of the breech-block. The rear end of the firing-pin is exposed in a slot 29 in one side of the breech-block and near the 15 rear end thereof; and the firing-pin passes lengthwise through the breech locking members and pivot and projects out through a slot 32 at the front end of the breech-block in position so as to engage the primer of 20 a cartridge, represented at 33, when the trigger is pulled. With the breech-block thrown forward, if the trigger is pulled the trigger performs the triple function; first, of pulling the rear end of the breech locking 25 brace down by means of the arm 28 so as to position the firing-pin in the path of the hammer; second, of locking the breech-block against recoil, by the solid block 2' of the receiver; and third, pulling the trigger re- 30 leases the hammer from the sear and the hammer flies around and strikes the firing-pin, as shown in Fig. 2, and discharges the piece, if the latter is loaded; it being understood that all the time the shaft 4 is under 35 tension of the mainspring or springs 5. Releasing the trigger allows the latter, acting under its spring 21, to resume its normal position; and in so doing, the arm 28 raises the rear end of the breech locking brace and 40 pushes it back in the space provided for it in its housing or case 16, thereby releasing the hammer, which flies around until it is intercepted by the sear lug 19.

In the movement of the hammer from the 45 firing position, shown in Fig. 2, to its normal position against the lug 19, the breech-block and its case are operated to eject the discharged shell and reload the piece, by the following mechanism: The rack gear 15 is 50 ordinarily disconnected from its operating gear 14, and when disconnected therefrom, a coiled spring 35 having one end fixed to a stationary part of the piece, and the other end fixed to the gear 15, will operate to 55 throw the breech-block and its case forward into closed, ready-to-fire position, represented in Figs. 1 and 2. It is only when the gears 15 and 14 are locked together, and during a portion of the period of time be- 60 tween the release of the hammer from the rear end of the breech-block and its return against the sear lug, as shown in Fig. 3, that these gears 14—15 turn in unison, and in so doing retract the breech-block. In

order to lock the gears together, the gear 15 65 has a spring-pressed pawl 36 which is engageable once each revolution of the pinion 14 with a lug or notch 37 on the pinion 14. The pawl 36 is released from the notch 37 by having its outer end engage a pin 38 projecting from the trigger. The moment the pawl is tripped by the projection 38 the two gears 14—15 are uncoupled, Fig. 7, and a spring 35 acts on the gear 15 and through the medium of the rack teeth 26 to throw 70 the breech-block and breech locking brace forward again in closed or ready-to-fire position. The empty shells are ejected on the retraction of the breech-block by any suitable form of ejecting mechanism 39, and 75 during the time that the breech-block is retracted a fresh shell from the magazine 40 is thrown up into the breech in line with the bore by a suitable elevator, represented at 41. This elevator is pivoted to the pivot- 80 pin 18 and extends forward in the breech and is normally depressed against the action of its spring 42 by the action of the front end of the breech-block carrier sliding up over the cam edges 43 of the elevator. As 85 here shown, this elevator is of simple construction, and comprises a curved metal carrier bent to form a cradle to receive a cartridge 33 when the elevator is depressed into line with the magazine 40. When a car- 90 tridge is in the elevator the primer end of the cartridge rests against the rear wall 44, and is gripped on top by the curved edges 44'. As the breech-block is retracted the spring 42 pushes up the front end of the 95 elevator, so that the bullet end of the cartridge is in line with the bore of the barrel. The rear portion of the cam edges 43 are 100 cut away so that the rim of the cartridge projects slightly above the elevator, as 105 shown in Fig. 3, so that when the breech-block case moves forward, it will, in riding over the carrier and sliding along the cam edges 43 thereof, catch in behind the rim of the cartridge and push the latter forward 110 into the chamber in the barrel. Provision is made so that before the elevator starts to descend, enough of the cartridge will be 115 shoved into the chamber so as to align it and support it, so that in the further continued forward movement of the breech-block the latter will push the cartridge clear into the chamber, and at the same time will, in riding up over the elevations 43 of the elevator, 120 depress the latter into line with the magazine, ready to receive a fresh cartridge for the next shot.

In practice, the parts being assembled and the mainspring or springs 5 wound up and placed on suitable tension, and the magazine 125 40 filled, the device is ready for use. Assuming that a cartridge is in the firing chamber, in order to discharge the piece the safety

catch 23 is pressed upward in gripping the stock, and the trigger pulled. In so doing, the rear end of the breech locking brace 17 is pulled down by the arm 28 with the trigger 5 to bring the firing-pin into line with the hammer 6. At the same time, the hammer, being released from the sear lug 19, flies around and strikes the firing-pin 24 and discharges the piece. In this first movement of the trigger and hammer to discharge the piece, the rack wheel 15 remains idle, but at the moment that the hammer strikes the firing-pin, the pinion 14 which moves opposite the pinion 13 has its notch 37 10 brought opposite to the spring-pressed pawl 36 on the rack pinion 15, so as to lock the two pinions 14-15 together. Releasing the trigger allows the spring 21 to act to push the breech locking brace back into the breech-block 16 and thereby release the hammer which flies on around for half a revolution until it is interrupted again by the sear lug 19. For a part of the period of this second movement of the hammer the gears 14-15 15 are locked together, resulting in the retraction of the breech-block and breech locking brace and the ejection of the cartridge, the lifting of the elevator, and the positioning of a fresh cartridge into line with the firing 20 chamber. Then the outer end of the pawl 36 strikes the pin 38 on the trigger and disconnects the pawl 36 from the gear 14 and allows the spring 35 to act by recoil to throw the breech-block and breech locking 25 brace forward and load the piece. Each time the trigger is pulled and then released this operation of firing and reloading is repeated, so long as the mainspring 5 is under suitable tension.

40 A gun of this sort is very light, and the stock is strong, since the tube 3 and its spring contained mechanism occupy but very little room, while at the same time this tube forms a metal reinforce for the stock.

45 By using a long coiled spring, like a curtain-rod spring, it is possible to get sufficient tension by which from forty to fifty shots or more may be fired, without rewinding the spring.

50 Another important feature is in the safety arrangement by which the firing-pin is normally out of the path of the hammer, so that if for any reason the hammer should break off or slip by the sear lug 19, the piece 55 could not be discharged, and the hammer could fly around and around without danger of exploding the piece. Also, the breech locking brace can not be pulled down by the trigger and arm 28 to place the firing-pin 60 in firing position, except when the breech-block and breech locking brace are clear forward, because otherwise the breech locking brace would strike on the top of the rear abutment 2'. When the breech locking

brace is down and in line with the rear 65 abutment 2', as shown in Fig. 2, the breech locking brace is securely braced against the recoil of the gun. This is also an important feature.

Having thus described my invention, what 70 I claim and desire to secure by Letters Patent is—

1. In a gun having a stock, the combination of a rotary hammer, spring mechanism for operating the hammer including a shaft 75 extending lengthwise of the stock, a spiral spring around the shaft and having suitable connections with the hammer to impel the hammer, and means for controlling the movements of the hammer. 80

2. In a gun, the combination of a spring-actuated rotary hammer, a trigger, means on the trigger forming a sear disposed in the path of the hammer to limit the movement of the latter, a pivoted breech locking 85 brace carrying a firing-pin, and connections between the free end of the breech locking brace and the trigger to place the firing-pin in the path of the hammer.

3. In a gun, the combination of a spring-actuated rotary hammer, a trigger, means on the trigger forming a sear disposed in the path of the hammer to limit the movement of the latter, a firing-pin, and means operated by the trigger for moving the firing-pin into and out of the path of the hammer. 95

4. In a gun, the combination of a spring-actuated rotary hammer, a trigger, means on the trigger forming a sear disposed in the path of the hammer to limit the movement 100 of the latter, a sliding breech locking brace pivoted at one end, a firing-pin carried by the breech locking brace, and connections between the free end of the breech locking brace and trigger to position the firing-pin 105 to be struck by the hammer when the latter is released by the trigger.

5. In a gun, the combination of a hammer, a sear and a trigger, and spring mechanism for operating the hammer, said spring 110 mechanism including a shaft having gear connections with the hammer, and a coiled spring around the shaft operative to rotate the latter.

6. In a gun, the combination of a hammer, 115 a sear and a trigger, and spring mechanism for operating the hammer, said spring mechanism including a shaft having gear connections with the hammer, a coiled spring around the shaft operative to rotate the latter, and key-winding mechanism to place said shaft on tension. 120

7. In a gun, the combination of a hammer, a sear and a trigger, spring mechanism for operating the hammer, said spring mechanism including a shaft having gear connections with the hammer, a coiled spring around the shaft operative to rotate the lat- 125

- te, and key-winding mechanism to place said shaft on tension, a pivoted breech locking brace carrying the firing-pin, and connections between the trigger and breech locking brace to move the firing-pin into and out of the path of the hammer.
8. The combination with the stock and breech of a gun, of a tube extending lengthwise through the stock, a hammer in the breech, a spiral spring mechanism in the tube and connected with the hammer for actuating the latter, and means including a trigger for controlling the movements of the hammer.
9. The combination with the stock and breech of a gun, of a tube extending lengthwise through the stock, a hammer in the breech, a spiral spring mechanism in the tube and connected with the hammer for actuating the latter, means including a trigger for controlling the movements of the hammer, and breech-block mechanism operative by said spring mechanism.
10. In a gun, the combination of a tube extending lengthwise of the stock, a shaft journaled in the tube, a mainspring connected with the shaft and wound around the shaft, the opposite end of the spring having connection with a key-winding ratchet mechanism, a hammer, gear connections between the hammer and shaft, and means including the trigger for controlling the action of the hammer.
11. In a gun, the combination of a tube extending lengthwise of the stock, a shaft journaled in the tube, a mainspring connected with the shaft and wound around the shaft, the opposite end of the spring having connection with a key-winding ratchet mechanism, a rotary hammer, gear connections between the hammer and shaft, and a trigger having means interposable in the path of the hammer to limit the movement of the latter.
12. In a gun, the combination of a tube extending lengthwise of the stock, a shaft journaled in the tube, a mainspring connected with the shaft and wound around the shaft, the opposite end of the spring having connection with a key-winding ratchet mechanism, a rotary hammer, gear connections between the hammer and shaft, a trigger having means interposable in the path of the hammer to limit the movement of the latter, a pivoted breech locking brace having a firing-pin, and connections between the trigger and breech locking brace for placing the firing-pin in and out of firing position with respect to the hammer.
13. In a gun, the combination of a tube extending lengthwise of the stock, a shaft journaled in the tube, a mainspring connected with the shaft and wound around the shaft, the opposite end of the spring
- having connection with a key-winding ratchet mechanism, a rotary hammer, gear connections between the hammer and shaft, a trigger having means interposable in the path of the hammer to limit the movement of the latter, a pivoted breech locking brace having a firing-pin, connections between the trigger and breech locking brace for placing the firing-pin in and out of firing position with respect to the hammer, said breech locking brace mounted on a sliding breech block, and connections between the shaft and said breech block for reciprocating the latter.
14. In a gun, the combination of a tube extending lengthwise of the stock, a shaft journaled in the tube, a mainspring connected with the shaft and wound around the shaft, the opposite end of the spring having connection with a key-winding ratchet mechanism, a rotary hammer, gear connections between the hammer and shaft, a trigger having means interposable in the path of the hammer to limit the movement of the latter, a pivoted breech locking brace having a firing-pin, connections between the trigger and breech locking brace for placing the firing-pin in and out of firing position with respect to the hammer, said breech locking brace mounted on a sliding breech block, and connections between the shaft and said breech block for reciprocating the latter.
15. In a gun, the combination of a spring-actuated hammer, a sear, a trigger for operating the same, a pivoted breech locking brace having a firing-pin, and a connection between the free end of the breech locking brace and trigger to place the firing-pin in and out of firing position.
16. In a gun, the combination of a rotary hammer, a spring-actuated trigger, a sear member rigid and integral with the trigger interposable in the path of the hammer, a pivoted breech locking brace having a firing-pin, and link connections between the breech locking brace and trigger for placing the firing-pin in firing position when the hammer is released from the trigger.
17. In a gun, the combination of a rotary hammer, a spring-actuated trigger, a sear member rigid and integral with the trigger interposable in the path of the hammer, a pivoted breech locking brace having a firing-pin, link connections between the breech locking brace and trigger for placing the firing-pin in firing position when the hammer is released from the trigger, a sliding breech block carrying the breech lock-

ing brace, rack and pinion mechanism, connected with the spring mechanism for operating the hammer, for actuating the breech locking brace carrier in one direction, 5 and independent spring mechanism for operating the breech block in the opposite direction.

18. In a gun, the combination of a rotary hammer and a sliding breech locking brace, 10 a spring-actuated shaft having gear connections with the hammer, severable connections between the shaft and breech locking brace for operating the latter in one direction, and a trigger, with means to control 15 the movements of the hammer and breech locking brace.

19. In a gun, the combination of a breech-block having a rack member, a gear for operating the rack member, means for 20 throwing the breech block normally in one direction, and mechanism connectible with the gear to operate the breech block in the opposite direction.

20. In a gun, the combination of a breech-block having a rack member, a gear engaged 25 with the rack, a pinion connectible and disconnectible with said gear, and spring-actuated means for operating said pinion.

21. In a gun, the combination of a sliding 30 breech-block having a rack portion, a gear engageable with said rack, a rotary hammer, a spring-actuated shaft, and gear connections between the shaft and the hammer and said gear to operate the hammer and said breech block.

22. In a gun, the combination of a sliding breech-block having a rack portion, a gear engaging with the rack, a loose pinion mounted 40 on the shaft with the gear, a rotary hammer, a pinion carried by the hammer, a mainspring shaft having a gear engaging said pinions, and trigger mechanism.

23. In a gun, the combination of a sliding breech-block having a rack portion, a gear 45 engaging with the rack, a loose pinion mounted on the shaft with the gear, a rotary hammer, a pinion carried by the hammer, a mainspring shaft having a gear engaging said pinions, means for connecting 50 and disconnecting said rack gear and its pinion, and trigger mechanism.

24. In a gun, the combination of a sliding breech-block having a rack portion, a gear engaging with the rack, a loose pinion 55 mounted on the shaft with the gear, a rotary hammer, a pinion carried by the hammer, a mainspring shaft having a gear engaging said pinions, means for connecting and disconnecting said rack gear and its 60 pinion, trigger mechanism, said rack gear operable in one direction when connected with its pinion, and means for operating it in the opposite direction when disconnected therefrom.

25. A gun having a stock and a receiver, 65 a mainspring tube passing through the stock and screwing into the receiver, a shaft in the tube extending therethrough, a mainspring secured to the shaft, key-winding mechanism connected with the spring to place the shaft 70 on tension, a hammer operated by the shaft, and a trigger.

26. A gun having a stock and a receiver, 75 a mainspring tube passing through the stock and screwing into the receiver, a shaft in the tube extending therethrough, a mainspring secured to the shaft, key-winding mechanism connected with the spring to place the shaft on tension, a hammer operated by the shaft, 80 a trigger, and a sliding breech locking brace operable in one direction through suitable connections with said shaft.

27. A gun having a stock and a receiver, 85 a mainspring tube passing through the stock and screwing into the receiver, a shaft in the tube extending therethrough, a mainspring secured to the shaft, key-winding mechanism connected with the spring to place the shaft on tension, a hammer operated by the shaft, 90 a trigger, and a sliding breech block operable in one direction through suitable connections with said shaft, said breech-block having a pivoted breech locking brace connected with the trigger.

28. A gun having a stock and a receiver, 95 a mainspring tube passing through the stock and screwing into the receiver, a shaft in the tube extending therethrough, a mainspring secured to the shaft, key-winding mechanism connected with the spring to 100 place the shaft on tension, a hammer operated by the shaft, a trigger, and a sliding breech locking brace carrier operable in one direction through suitable connections with said shaft, said carrier having a pivoted breech locking brace connected with the trigger, 105 said last-named connections comprising a rigid arm on the trigger engaging a lengthwise slot in the breech locking brace.

29. A gun having a stock and a receiver, 110 a mainspring tube passing through the stock and screwing into the receiver, a shaft in the tube extending therethrough, a mainspring secured to the shaft, key-winding mechanism connected with the spring to place the shaft on tension, a hammer operated by the shaft, a trigger, and a sliding breech block operable in one direction 115 through suitable connections with said shaft, said breech block having a pivoted breech locking brace connected with the trigger, said receiver having an abutment for the rear end of the breech locking brace when the latter is pulled down.

30. A gun having a stock and a receiver, 120 a mainspring tube passing through the stock and screwing into the receiver, a shaft

- in the tube extending therethrough, a main-spring secured to the shaft, key-winding mechanism connected with the spring to place the shaft on tension, a hammer operated by the shaft, a trigger, and a sliding breech block operable in one direction through through suitable connections with said shaft, said last-named connections including rack and pinion mechanism.
- 10 31. In a gun, the combination of a rotary hammer, spring mechanism for operating the latter, a trigger, a sear projection on the trigger engaging the hammer, and a firing-pin operable by the hammer, and a pivoted breech locking brace mounted in a sliding breech block, said breech locking brace carrying said firing-pin and connections between the trigger and breech locking brace for oscillating the latter upon the 20 operation of the trigger.
32. In a gun, the combination of a rotary hammer, spring mechanism for operating the latter, a trigger, a sear projection on the trigger engaging the hammer, a firing-pin operable on by the hammer, and means connected with the trigger for placing the firing-pin in and out of operative position with respect to the hammer.
33. In a gun, the combination of a hammer capable of revolving a plurality of times in the same direction, means for causing it to revolve, a trigger, a detent on the trigger interposable in the path of the hammer, a firing-pin, a rockable support for the
- firing-pin, and connections between said support and trigger for rocking it on the operation of the trigger.
34. In a gun, the combination of a hammer capable of revolving a plurality of times in the same direction, means for causing it to revolve, a trigger, a detent on the trigger interposable in the path of the hammer, a firing-pin, a pivoted breech locking brace carrying the firing-pin, and connections between the trigger and breech locking brace for positioning the firing-pin in the path of the hammer.
35. In a gun, the combination of a hammer capable of revolving a plurality of times in the same direction, means for causing it to revolve, a trigger, a detent on the trigger interposable in the path of the hammer, a firing-pin, a pivoted breech locking brace carrying the firing-pin, connections between the trigger and breech locking brace for positioning the firing-pin in the path of the hammer, a sliding breech block, rack and pinion mechanism for operating the breech block, and means for operating said rack and pinion coördinately with the action of the hammer.

In testimony whereof I have hereunto set my hand in presence of two subscribing witnesses.

RICHARD E. JEFFERY.
